ISOMERIZATION OF NORMALLY LIQUID PARAFFINS

Aristid V. Grosse, Bronxville, N. Y., and Herman Pines, Riverside, Ill., assignor to Universal Oil Products Company, Chicago, Ill., a corporation of Delaware

No Drawing. Application May 25, 1943,
Serial No. 488,438

12 Claims. (Cl. 260—683.5)

This application is a continuation-in-part of our co-pending application Serial #282,083 filed June 30, 1939, now Patent No. 2,336,862, which is a continuation-in-part of application Serial #118,587 filed December 31, 1936.

This invention relates particularly to the isomerization of straight chain paraffin hydrocarbons which are normally liquid.

In a more specific sense, the invention is applicable not only to individual paraffin hydrocarbons of normal straight chain structure but also to hydrocarbon mixtures containing these compounds in substantial percentages such as straight run gasolines and their fractions, which contain in addition to paraffin hydrocarbons of highly knocking characteristics other hydrocarbons comprising some paraffins of branched chain structure and the usual run of naphthenes and aromatics. The isomerization of individual paraffin hydrocarbons such as n-pentane or n-hexane is frequently desirable in the manufacture of derivates since the isomeric compounds are more reactive and, in the case of gasoline or gasoline fractions, the isomerization has the effect of increasing the antiknock value of the gasolines to a marked extent as will be shown in later examples.

There should be no need for extensively recounting the number of possible isomers of paraffin hydrocarbons since these are all predictable on the present theories of organic chemistry and are well known to those familiar with this subject. However, the following table is shown to indicate in a general way the change in structure and properties of normal paraffin hydrocarbons and their isomers, particularly since the pentanes constitute some of the lower-boiling constituents of ordinary gasolines.

ures are not available for the neo-pentane. Similarly, the isomeric hexanes, heptanes, and octanes will show the same progressive relationships as their structure becomes more condensed. As the molecular weight of paraffin hydrocarbons increases, the number of possible and known isomers increases more than arithmetically so that in cases of isomerization involving mixtures of n-paraffins and particularly n-paraffins in admixture with other hydrocarbons in gasolines, the determination of the extent of isomerization is not possible by analytical methods but can be estimated from the observed change in antiknock value.

In one specific embodiment, the present invention comprises treatment of hydrocarbon mixtures containing normally liquid paraffins and cyclic compounds with catalysts comprising halides of the Friedel-Crafts type and hydrogen halides to effect isomerization of the normally liquid paraffins.

We have found that the results obtained when treating hydrocarbon fractions boiling within the gasoline range containing paraffinic hydrocarbons and the usual run of cyclic hydrocarbons such as naphthenes and aromatics are considerably improved over those obtained when treating the paraffin hydrocarbons in the absence of these cyclic hydrocarbons.

In the isomerization of normally liquid paraffin hydrocarbons by contact with halide catalysts of the Friedel-Crafts type in the presence of a hydrogen halide under isomerizing conditions of temperature and pressure, considerable decomposition and other side reactions occur simultaneously with the isomerization reaction. The fragmental hydrocarbons formed during the decomposition unite with the halides of the Friedel-

Compound	Formula	Boiling point	Density	Octane number
n-Pentane.....	$\text{CH}_3(\text{CH}_2)_2\text{CH}_3$	° C. 36.3	0.6475 @ 0° C.....	63
Iso-pentane.....	$\begin{array}{c} \text{CH}_3 \\ \\ \text{CH}(\text{CH}_3)\text{CH}_2 \\ \\ \text{CH}_3 \end{array}$	23	0.6394 @ 0° C.....	63
Neo-pentane...	$\text{C}(\text{CH}_3)_3$	9.5	0.6251 @ 14.4° C.....	63

It will be observed from the above that, as the structure of the molecule becomes more compact, boiling point and specific gravity both decrease while the antiknock value as expressed by octane number generally increases although fig-

Crafts type to form complexes commonly called "sludge." This formation of sludge increases to a considerable extent the catalyst consumption per unit weight of paraffin hydrocarbon isomerized and introduces many operating difficulties

in the process such as separation and disposal of the sludge. If, however, straight run gasoline fractions containing the usual percentages of paraffins and cyclic compounds such as aromatics are isomerized under similar conditions, the amount of decomposition and other side reactions is considerably decreased. Particularly suitable stocks for treatment in the process of the present invention are straight run gasoline fractions, for example, the hexane fraction obtained from straight run gasolines such as Michigan or Mid-Continent gasolines, containing aromatic hydrocarbons usually consisting of benzene in percentages of the order of 0.3 to about 2%. Aromatic hydrocarbons such as benzene and toluene which are ordinarily present in fractions of straight run gasoline are particularly effective in inhibiting decomposition reaction during the isomerization process.

There are several alternative catalysts which may be employed in accomplishing the isomerization reaction among the paraffin hydrocarbons. While they may be used more or less interchangeably, some are more effective than the others and it is not intended to infer that they are definitely equivalent. Among the compounds which may be employed are the halides of the Friedel-Crafts type such as aluminum halides, zirconium halides, zinc halides, iron halides, boron fluoride, either alone or in admixture with one another, or in admixture with compounds such as antimony, arsenic and bismuth compounds which form low-melting catalyst mixtures. Suitable catalysts may be also derived by the reaction of these halides with hydrocarbons to form catalytically active complexes. The solid catalysts may be used in a granular state or deposited upon supporting materials such as alumina, bauxite, activated clays, activated carbon, and other well-known supporting agents. Extensive experiments have indicated that best results are obtained when a hydrogen halide is present in the reaction zone along with these compounds. There will be some variations in relative amounts of Friedel-Crafts type compounds and hydrogen halides used at optimum treating conditions but the determination of these ratios is somewhat a matter of experiment. The combination of aluminum chloride and hydrogen chloride is usually preferable over the other possible combinations. Ordinarily when utilizing this particular combination, a hydrogen chloride concentration is usually below approximately 40 mol percent of the charge.

The specific conditions of temperature, pressure and hydrogen halide concentration are dependent primarily upon the particular hydrocarbon mixture and catalyst used in the isomerization reaction. However, in the broad aspects of the invention, the temperature will vary from 10° to about 250° C. When a specific hydrocarbon fraction such as a hexane fraction obtained from a straight run gasoline and containing the usual amount of cyclic hydrocarbons such as an aromatic content of about 0.5 to 1.5% is contacted with aluminum chloride in the presence of hydrogen chloride, the desired operating temperature for said results will ordinarily be within the range of 10° to about 200° C. When various other catalysts such as zinc chloride and zirconium chloride are utilized, temperatures in the neighborhood of 250° C. may be used.

The process may be operated under batch or continuous conditions and either in liquid, mixed or vapor-phase as may be desirable or expedient in view of the particular catalyst combination

chosen and the hydrocarbon mixture undergoing treatment. A simple method of operation consists in adding 5 to 10 percent of granular anhydrous aluminum chloride to a treating vessel containing hydrocarbons and provided with a mechanical agitating device of some description. It is best to employ a treater which can be sealed from atmospheric contact and which can be operated under pressure if necessary. The solid catalyst is then kept in suspension by moderate agitation while introducing a slow stream of hydrogen chloride.

In another type of operation which accelerates the rate of isomerization, the hydrocarbon mixture may be kept at its boiling point by moderate heating under reflux conditions with the granular chloride maintained in suspension by the ebullition, while the hydrogen chloride is again added in a slow stream. In this type of operation any desired superatmospheric pressure may be employed to permit the use of any desired temperature. Vapor-phase operations may be conducted by passing vapors of hydrocarbons mixed with a small amount of hydrogen chloride over solid granular catalysts comprising the preferred metal halides, an example of such catalysts being the composite produced by impregnating the pores of activated carbons with sublimed aluminum chloride.

In the case of readily vaporizable metallic halides such as aluminum chloride, it may be sublimed directly into a stream of hydrocarbon vapors and the hydrogen chloride followed by settling of spent catalyst and fractionation of the products.

The following examples are introduced to exemplify the improved results obtained in the operation of the process, but they are not given with the intention of limiting the scope of the invention in exact correspondence with the numerical data presented.

Example I

In this example, the gasoline fraction boiling within the range of 50° to 90° C. obtained from a highly paraffinic Michigan gasoline was treated. The fraction had an octane number of 54 and corresponded roughly to a mixture of hexanes and cyclic compounds such as cyclohexane and benzene. This fraction was subjected to isomerization for the improvement of its antiknock value in the presence of aluminum chloride and hydrogen chloride at two temperatures to observe the effect at each. The gasoline fraction was placed in a pressure vessel, aluminum chloride was added, and the heating was conducted over a period of 6 hours after which the vessel was cooled and gaseous liquid hydrocarbons recovered and examined. The following table gives the principal results obtained in the two runs.

Temperature	Run #1 150° C.	Run #2 200° C.
Charge in treater "gasoline," pts. by wt.	200.0	200.0
AlCl ₃ , pts. by wt.	20.0	20.0
HCl, pts. by wt. (approximate)	5	5
Maximum pressure, atm.	16	45
Octane No. of product	65	72
Liquid product per cent by wt. of chg.	87	75.3

The octane number of the product was considerably improved over that of the charge with only moderate losses of charge due to gas formation and minor amounts of aluminum chloride-hydrocarbon complexes.

Example II

A pentane fraction containing about 0.5 volume percent benzene was contacted with aluminum chloride in the presence of 10 mol percent of hydrogen chloride. The temperature and pressure in the reaction zone was 100° C. and 500 pounds per square inch gauge. A once through yield of about 52 volume percent of isopentane was produced per pass with substantially no production of light gases or hydrocarbons boiling higher than normal pentane. A substantial portion of the benzene was recovered in the product.

In a second experiment in which normal pentane free of benzene was contacted with aluminum chloride and hydrogen chloride under the same conditions, a once through yield of about 29 volume percent isopentane was obtained. However, about 30 volume percent of the normal pentane was converted to isobutane and hydrocarbon boiling higher than normal pentane.

In comparing the results of the two experiments given above, it is evident that the presence of the aromatic hydrocarbon, namely benzene, inhibited the decomposition of the normal pentane to higher and lower boiling hydrocarbons. It is apparent that on a recycle basis, the advantage obtained by the addition of benzene would be considerably more prominent in that the efficiency of the isomerization operation in which benzene is present is about 97% while in the second experiment where pentane alone is isomerized, the efficiency is below about 50%.

We claim as our invention:

1. A process for isomerizing a normally liquid paraffin hydrocarbon boiling in the gasoline range which comprises subjecting said paraffin, while in admixture with a non-olefinic cyclic hydrocarbon, to the action of an isomerizing catalyst of the Friedel-Crafts type in the presence of added hydrogen halide and under isomerizing conditions of temperature, pressure and time, and correlating the amount of hydrogen halide and said isomerizing conditions of temperature, pressure and time to convert a substantial portion of said paraffin into an isomer or isomers thereof having the same molecular weight as said paraffin.

2. A process for isomerizing a normally liquid paraffin hydrocarbon boiling in the gasoline range which comprises subjecting said paraffin, while in admixture with a non-olefinic cyclic hydrocarbon, to the action of an aluminum halide in the presence of added hydrogen halide and under isomerizing conditions of temperature, pressure and time, and correlating the amount of hydrogen halide and said isomerizing conditions of temperature, pressure and time to convert a substantial portion of said paraffin into an isomer or isomers thereof having the same molecular weight as said paraffin.

3. A process for increasing the anti-knock properties of gasoline boiling paraffins which comprises subjecting a normally liquid hydrocarbon fraction boiling in the gasoline range and containing paraffins of relatively low anti-knock

value and non-olefinic cyclic hydrocarbons to the action of an isomerizing catalyst of the Friedel-Crafts type in the presence of an added hydrogen halide under isomerizing conditions of temperature, pressure and time, and correlating the amount of hydrogen halide and said isomerizing conditions of temperature, pressure and time to convert a substantial portion of the paraffins contained in said fraction into isomers thereof having the same molecular weight as and of higher anti-knock properties than said paraffins.

4. The process as defined in claim 3 further characterized in that said isomerizing catalyst comprises an aluminum halide.

5. The process as defined in claim 3 further characterized in that said isomerizing catalyst comprises aluminum chloride and in that said hydrogen halide is hydrogen chloride.

6. The process as defined in claim 1 further characterized in that said isomerizing catalyst comprises an aluminum halide and in that said paraffin contains less than 7 carbon atoms.

7. The process as defined in claim 1 further characterized in that said isomerizing catalyst comprises aluminum chloride and in that said hydrogen halide is hydrogen chloride.

8. The process as defined in claim 1 further characterized in that said cyclic hydrocarbon is a naphthene.

9. The process as defined in claim 2 further characterized in that said cyclic hydrocarbon is a naphthene.

10. The process as defined in claim 3 further characterized in that said cyclic hydrocarbons comprise a naphthene.

11. A process for increasing the anti-knock properties of gasoline boiling paraffins which comprises subjecting a normally liquid hydrocarbon fraction boiling in the gasoline range and containing paraffins of relatively low anti-knock value and a naphthene to the action of an aluminum halide in the presence of an added hydrogen halide under isomerizing conditions of temperature, pressure and time, and correlating the amount of hydrogen halide and said isomerizing conditions of temperature, pressure and time to convert a substantial portion of the paraffins contained in said fraction into isomers thereof having the same molecular weight as and of higher anti-knock properties than said paraffins.

12. A process for isomerizing a normally liquid paraffin hydrocarbon boiling in the gasoline range which comprises subjecting said paraffin, while in admixture with a naphthene, to the action of aluminum chloride in the presence of added hydrogen chloride and under isomerizing conditions of temperature, pressure and time, and correlating the amount of hydrogen chloride and said isomerizing conditions of temperature, pressure and time to convert a substantial portion of said paraffin into an isomer or isomers thereof having the same molecular weight as said paraffin.
